UNITED STATES PATENT OFFICE.

RICHARD PETERSON, OF PHILADELPHIA, PENNSYLVANIA.

DESIGN FOR A COOKING-STOVE.

SPECIFICATION forming part of Design No. 12,512, dated October 4, 1881.

Application filed May 26, 1881. Term of patent 7 years.

To all whom it may concern:

Be it known that I, RICHARD PETERSON, a citizen of the United States, residing in Philadelphia, Pennsylvania, have invented a new and original Design for a Cooking-Stove, of which the following is a specification.

My design for a cooking-stove is represented in the accompanying drawings, Figure 1, Sheet 1, being a view of the complete stove; and Fig. 2, Sheet 2, a view of the panel which ornaments the main door of the stove.

A is the main oven-door, B the end fire-door, D D the front fire-doors, E and F the doors of the reservoir and heating-closet extension, and G the feet, of the stove.

The principal ornament of the main door A is the central panel, *a*, which is shown in detail in Fig. 2, the decoration of this panel comprising the representation *b* of a shock of corn, which occupies a central position in the panel, and is surrounded by a circular border, *d*, composed of two bent cornstalks having ears and leaves, as shown. The door A is further ornamented by a representation of a stalk of corn extending diagonally across the door beneath the panel, and the door A as well as the smaller doors B, D, E, and F of the stove, have corner

and border ornamentation of a character too fully shown to need detailed description. The main feature of each of the small doors, however, is the central ornament, *e*, which consists of the representation of a partially-stripped ear of corn.

Each of the feet G of the stove has an ornament, *f*, also representing a partially-stripped ear of corn.

I claim—

1. The design for the central panel or plate, *a*, said design comprising the representation of a shock of corn surrounded by a border composed of representations of bent stalks of corn, as shown and described.

2. The design for the main door A, said design comprising, essentially, the central panel, *a*, and the representation of a stalk of corn extending diagonally across the door beneath the panel, as shown and described.

In testimony whereof I have signed my name to this specification in the presence of two subscribing witnesses.

RICHARD PETERSON.
